(57) **CLAIM**

The ornamental design for a game turn device, as shown and described.

DESCRIPTION

FIG. 1 is an exploded isometric view of a game turn device showing my new design;

FIG. 2 is an assembled isometric view thereof;

FIG. 3 is a top plan view thereof;

FIG. 4 is a bottom plan view thereof;

FIG. 5 is a front elevational view thereof;

FIG. 6 is a rear elevational view thereof;

FIG. 7 is a right elevational view thereof; and,

FIG. 8 is a left side elevational view thereof.

In the drawings the broken lines illustrate portions of the game turn device that form no part of the claimed design.
